UNITED STATES PATENT OFFICE.

ALFRED CLEMENT STEWART, OF SANTA PAULA, CALIFORNIA.

AUTOMATIC REGULATOR FOR LIQUID-FUEL BURNERS.

SPECIFICATION forming part of Letters Patent No. 736,563, dated August 18, 1903.

Application filed October 27, 1902. Serial No. 129,038. (No model.)

To all whom it may concern:

Be it known that I, ALFRED CLEMENT STEWART, a citizen of the United States, residing at Santa Paula, in the county of Ventura and State of California, have invented a new and useful Automatic Regulator for Liquid-Fuel Burners, of which the following is a specification.

An object of this invention is to provide a device adapted for automatically regulating the flow of oil and air or steam to a hydrocarbon-burner of the atomizing type, the same being adapted for successful operation with heavy oils carrying solid impurities and being self-contained and not liable to get out of order. This device comprises a body having two ways and valve-seats therein, valves for said seats, a rod for operating said valve, means for yieldingly holding the valves open, and fluid-controlled means to operate said rod for closing the valves. Said rod is desirably arranged for positively opening said valves and for positively closing one of said valves only, means being provided for yieldingly forcing the other valve toward its valve-seat and fluid-operated means being provided for operating the rod for closing the valves. By making the valves operate independently of each other, so far as their positive closing is concerned, it is possible to provide for more simple construction, and the oil-valve is made more accessible for cleaning.

The invention relates to the construction and arrangement of the entire device and of portions thereof, as will be more fully understood by the accompanying drawings and the following specification.

Another object of the invention is to provide for maintaining correct proportions between the steam or other atomizing fluid and oils of different gravities, and this is done by providing interchangeable valve-seats for the oilway.

The accompanying drawings illustrate this invention.

Figure I is a general view showing my regulator in use with an atomizing hydrocarbon-burner of any desired construction. Fig. II is a detached elevation of the regulator viewed from the left in Fig. I. Fig. III is a plan of the same. Fig. IV is an axial section on line IV IV, Figs. II and III, looking left.

Fig. V is a plan section on line V V, Fig. IV. Fig. VI is a plan section on line VI VI, Fig. IV. Fig. VII is a detail of a set of removable and interchangeable valve-seats for the oilway.

1 is a hollow open-ended member having an expansive medium way 2 with an inlet 3, an outlet 4, and a valve-seat 5 therebetween. 6 is a perforated head for one end 7 of said member, the perforation 8 thereof communicating with the opening 9 in said end through a nipple 10, by which said head 6 is desirably connected with the member 1. 11 is a duplex diaphragm. 12 is a diaphragm member fastened at its center to said head 6 and having a perforation 13 communicating with said end opening 9. 14 is a second diaphragm member fastened at its edges to the first diaphragm member. 15 is a second head fastened to the second diaphragm member, at the center thereof. 16 is a valve for said valve-seat 5. 17 is a valve-rod connecting said second head 15 with the valve 16. The purpose of the heads is to reinforce the diaphragm members and prevent their rupture.

18 and 19 designate means for yieldingly collapsing the double diaphragm, and thereby holding the valve 16 open. Said means desirably comprises a spiral spring and the yoke 19, which has a boss 20, engaging the head 15, and having a socket 21, in which a projecting portion 22 of the valve-rod 17 extends, thus to prevent the yoke from lateral or endwise displacement. The way 2 is desirably for the expansive fluid, as air or steam, by which the atomizer 23 is operated. The expansive fluid will be supplied to the inlet 3 by means of a pipe 24 from the steam-boiler 25 in case steam is used or from any suitable intermediate means (not shown) operated by steam-pressure from said boiler. It is deemed sufficient for the explanation of this invention that it be illustrated simply as connected by the pipe 24 with the boiler 25, so that as the steam-pressure rises in the boiler the diaphragm 11 will be distended by the steam, thus forcing the valve 16 down toward the valve-seat 5, thereby closing partially or wholly the orifice 2.

26 is a second open-ended member fastened to said first member 1 and having a perforation 27 communicating with the way 2 of said

- first member and also having an inlet 28 and outlet 29 and a valve-seat 30 therebetween. 31 is a pin fitted in said perforation 27 and forming an extension of the valve-rod 17. 5 32 is a valve for said second valve-seat 30, and 33 a valve-stem therefor operated by said pin 31 and forming a further extension of said valve-rod 17. 34 designates means for yieldingly seating said second valve 32. 35 is a 10 closure for that end 36 of said second member which is opposite the diaphragm. Said closure is desirably a cap having a screw-threaded portion 37, which screws into the end 36 of the member 26. 15 38 is a guide for the upper end of the valve-stem 33, the same being desirably a socketed boss projecting in from the cap and around which the spiral spring 34 is mounted and by which it is held in place. The upper end 20 of the valve-stem 33 is desirably smooth and plays freely back and forth in the socket 39 of the boss 38. 25 The valve 32 is desirably provided with an angular boss 40 and is internally screw-threaded to screw upon the screw-threaded portion 41 of the valve-stem 33. 30 42 is a jam-nut by which the valve 32 is fixed at any desired place on the valve-stem 33. 43, 44, and 45 are interchangeable valve-seats for the oilway 46. 35 47 designates screws by which the requisite oil-valve seat will be fastened in place in the oilway. 48 designates rivets fastening the dia- 40 phragm member 12 to the first head 6. Desirably the second head 15 is screwed onto the lower end of the valve rod 17 and is then fastened permanently by battering or riveting the rod 17 thereon, as indicated at 49 in Fig. IV. 45 50 is a shoulder desirably in the form of a jam-nut, which is fixed on the valve-rod 17. The valve 16 is desirably screwed on the upper end of the valve-rod 17 and then locked by a cotter-pin 51. 50 52 is a socket in the inner end of the valve-rod 17 to seat the lower end of the pin which serves as a center for the stem 7 to hold the valve true relative to its seat 5. Desirably the valve-stem 33 simply abuts against the upper end of the pin 31. 55 53 and 54 are the valves for controlling the supply of expansive fluid and oil, respectively, to the inlets 3 and 28. 60 55 The members 1 and 26 are readily detached from each other, being desirably fastened together by the screw-threaded boss 55 on the member 26, screwed into the upper end of the member 1, and when thus fastened together 65 the two members form a practically unitary body having the steamway 2 and oilway 46 therein. 65 In practical operation the steam acting on the inner sides of the diaphragm members will distend the diaphragm and bring the valve 16 positively toward the valve-seat 5 to partially or wholly close the same. At the

same time the spring 34 forces the valve 32 toward the valve-seat 43 and the valve-stem 33 impinges on the pin 31, which is supported 70 by the valve-rod 17.

In adjusting the appliance for practical use the valve 32 will be screwed onto the valve-stem 33 to such a point that when the valve 16 is seated the valve 32 will be held 75 slightly above its seat, so as to allow sufficient oil to pass through to maintain a pilot-light at the burner. 56 designates a vent in valve 17 to allow a small amount of expansive fluid to pass through the way 2 when the valve 16 80 is fully seated, thus to at all times maintain the pilot-light at the burner so long as the fuel is not shut off by the supply-valve.

The interchangeable valve-seats 43, 44, and 45 are respectively furnished with orifices 85 *a b c* of different sizes. For oil which flows readily the valve-seat having a smaller-size orifice will be employed, while for thick oil a valve-seat having a larger orifice will be employed. By this arrangement the operator 90 may adjust the appliance for satisfactory use of any determined oil. When the valve is at any determined point above its valve-seat, the effective area of opening for the passage of oil will be determined by the circumference 95 of the opening in the valve-seat and the distance between the valve and its seat, said opening being increased or decreased relative to the steam-passage at 5 by applying the valve-seat 43, 44, or 45 having the larger or 100 smaller opening, as required.

Some oils are so thick that they will scarcely flow through a one-inch pipe, whereas other oils flow almost as freely as water. Consequently it is necessary in some instances to 105 provide for a very large opening through which the oil may flow and in other instances a very small opening, while the flow of the expansive fluid is simply determined by its pressure regardless of the consistency of the 110 oil.

In constructing a regulator from the manufactured parts the same are assembled as follows: The upper member 12 of the dia- 115 phragm is riveted to head 6. The lower mem- 120 ber 14 is then placed against it and their edges turned together to form steam or air tight joint. The jam-nut 50 is then screwed on rod 17 and the lower end of the rod passed through the hole of the lower member of dia- phragm and screwed into the lower head 15, thus clamping the diaphragm tightly between the jam-nut 50 and said head 15. Then the rod will be riveted, as shown at 49, a suffi- 125 cient portion of the rod projecting beyond the head 15 to form a guide for the yoke 19. The upper head 6 is then screwed to the steam body 1 by means of the nipple 10. The valve 16 is screwed upon the top of the rod 17 and fastened by a split key 51. The 130 oil member 26 is then screwed into the upper end of steam member 1. Removable valve-seat 43 is then fastened in place by means of screws 47. Pin 31 is then placed in hole 27.

The oil-valve 32 is then screwed on valve-stem 33 and jammed in place by jam-nut 42 and then placed on valve-seat 43. Then spiral spring 34 is placed upon valve 32 and then cap 35 is screwed in place at the upper end of the oil member. Then the springs are secured in place by eyebolts 57, passed through lugs 58, which project from the body of the appliance, and nuts 59 are screwed on the ends of the bolts 57 and against the lugs 58. Then the yoke 19 is brought in position below the head 15 and the ends thereof are caught into eyes 60 at the lower ends of the springs 18. Then the nuts 59 will be tightened to appropriate tension to normally hold the diaphragm collapsed and the valves open.

Access to the interior of the oilway and to the valve 32 for the purpose of cleaning the same or removing any obstruction may be had by unscrewing the cap 35, thus allowing all of the parts pertaining to the oil member 26 to be removed without disturbing any of the other parts.

Now having described my invention, what I claim, and desire to secure by Letters Patent of the United States, is—

1. A body having two ways and valve-seats therein; valves for said seats; a rod arranged for positively opening both valves and for positively closing one of said valves only; means for yieldingly closing the other valve; means for yieldingly holding the rod in position for opening both valves; and fluid-operated means for operating the rod for closing the valves.

2. A body having two ways and valve-seats therein; valves for said seats; a rod arranged for positively opening both valves and for positively closing only one of said valves; means for yieldingly closing the other valve; means for yieldingly holding the rod in position for opening both valves; and a diaphragm arranged to operate the rod and to receive pressure of fluid from that way the valve of which is positively closed by said rod.

3. A hollow open-ended member having an inlet and an outlet, and a valve-seat therebetween; a perforated head for one end of said member, the perforation communicating with the opening in said end; a diaphragm member fastened at its center to said head and having a perforation communicating with said end opening; a second member fastened at its edges to the first diaphragm member; a second head fastened to the second diaphragm member; a valve-rod connecting said second head with the valve; a second open-ended member fastened to said first member and having a perforation communicating with the way of the first member, and also having an inlet and an outlet and a valve-seat there-

between, a pin in said perforation and forming an extension of said valve-rod; a valve for said second valve-seat; a valve-stem therefor operated by said pin; means for yieldingly seating said second valve; means for normally collapsing the diaphragm; and a closure for the end of the second member opposite the diaphragm.

4. In a device of the class described, in combination, a body having two ways and valve-seats therein, valves for said seats, a rod arranged for positively opening both valves and for positively closing only one of said valves, means for yieldingly closing the other valve, 70 a diaphragm arranged to operate the rod and to receive pressure of fluid from that way the valve of which is positively closed by said rod, means for yieldingly supporting and strengthening said diaphragm, and means for yieldingly operating said diaphragm to normally hold said rod in position for operating both valves.

5. In a device of the class described, in combination, a body having two ways and valve-seats therein, valves for said seats, a rod arranged for positively opening both of said valves and for positively closing only one of said valves, means for yieldingly closing the other valve, a two-part diaphragm arranged 85 in operative connection with said rod, an opening communicating from one of said ways between the parts of said diaphragm, a yoke bearing against said diaphragm, and means yieldingly forcing said yoke against 90 said diaphragm to normally hold said rod in position for opening said valves.

6. In a device of the class described, in combination, a body having two ways and valve-seats therein, valves for said seats, a rod arranged for positively opening both said valves and for positively closing one of said valves, means for yieldingly closing the other valve, a two-part diaphragm, heads supporting and strengthening the respective parts of said 105 diaphragm, a way opening through one of said heads and between the parts of said diaphragm, the other head operatively connected with said diaphragm, a yoke bearing against the last-named head, and means for yieldingly operating said last-named head to hold 110 said rod normally in position to open both said valves.

In testimony whereof I have signed my name to this specification, in the presence of 115 two subscribing witnesses, at Los Angeles, in the county of Los Angeles and State of California, this 8th day of October, 1902.

ALFRED CLEMENT STEWART.
